CLAIM

The ornamental design for a cheese board set as shown and described.

DESCRIPTION

FIG. 1 is a perspective view of a cheese board set showing the new design in a retracted state;

FIG. 2 is a perspective view of the cheese board set in an extended state;

FIG. 3 is a perspective view thereof, with its side drawers detached;

FIG. 4 is a front elevation view of the cheese board set in a retracted state;

FIG. 5 is a rear elevation view thereof;

FIG. 6 is a left elevation view thereof;

FIG. 7 is a right elevation view thereof;

FIG. 8 is top plan view thereof; and,

FIG. 9 is a bottom plan view thereof.

The broken lines and unshaded surfaces bounded by broken lines form no part of the claimed design.

1 Claim, 9 Drawing Sheets
